FRAMELESS BUILDING

Walter H. Stulen, Pittsburgh, Pa.

Application March 30, 1935, Serial No. 13,868

14 Claims. (Cl. 189—34)

This invention relates to buildings and more particularly to fabricated frameless metallic structures and to methods of manufacturing such structures.

In building houses, stores, garages and so forth it has been the standard practice for many years to employ a relatively heavy frame of metal or wood which serves as a skeleton of strength or load-carrying members with the walls, floors and ceiling of the building being constructed on and secured to the skeleton framework. In more recent years it has been proposed to dispense with the skeleton frame structure and to make the walls, ceilings, floors, etc. of sufficient strength so that they serve to eliminate the skeleton frame. The frameless type of building is particularly adapted to be made up in sheet metal or other metallic structures and theoretically provides a stronger and a more durable building which should be rapid to construct.

Prior to my invention, the frameless type of building, particularly when constructed from metal, has, however, proven more costly and more difficult to construct than the old skeleton frame building for the reason that trouble was experienced in properly fabricating the metallic members on location and because likewise the metallic members were of such a complicated nature as to materially increase the cost of the building. Certain of the cost of the metallic members was due, no doubt, to the very complicated shapes which they assumed, thereby necessitating expensive rolling and pressing equipment for their manufacture. Likewise, it has been the prevailing practice to make the metal members entirely from sheet metal which is solid the full length of the members. Constructions of this character necessitated considerable material being used in the manufacture of the members with the requisite that the thickness of the sheet metal be maintained relatively great.

As a result of the difficulty of fabricating the metallic structures on the job and in the field and because of the expense attending their manufacture, the frameless type of building has never proven popular or been completely accepted even though admittedly it has theoretical advantages such as increased strength, lower weight and speed of assembly if it could be handled properly.

It is the object of my invention to avoid and overcome the difficulties attending the construction and use of prior known fabricated frameless metallic structures by the provision of a building unit which readily adapts itself to fabrication into novel panels of any desired size, shape and

strength, which panels can readily be made up in the field to form a new type of a frameless structure. It is likewise the object of my invention to provide an inexpensive, rapid and highly effective method for the commercial manufacture of the building units.

My invention is predicated upon my discovery that individual units of considerable strength and simplicity can be constructed from sheet metal and rolled load-carrying members by a spot-welding assembly operation with a minimum of metal being employed in the construction and yet obtaining the necessary strength. The individual units are particularly adapted to be readily fabricated into panels for use as floors, walls, and the like. This fabrication is achieved by welding a plurality of units placed side by side into boundary channels of sheet metal to form panels which are adapted in construction to be secured together at their edges with other panels to form a building.

In the practice of my invention I first cut a relatively large piece of sheet metal without waste to form a plurality of strips of metal comprising square or polygon-shaped portions which are secured integrally together at their corners on a common diagonal, as will be best understood by reference to the drawings and as hereafter explained in detail. The sheet metal strips so formed are then bent on the diagonal and are spot-welded to a longitudinally-extending load-carrying element such as an angle-iron. The side portions of the sheet metal which are in the form of triangular extending tabs are likewise spot-welded at their extreme edges to longitudinally-extending load-carrying elements which preferably are angle-irons.

The units so produced are fabricated into any desired structure and as for example they can be placed in side-by-side relation with their ends received in sheet metal channels where they are welded. Sheet metal channels may likewise be welded to the sides of the end units so that a complete panel of fabricated units is produced. A plurality of strengthening metal sections is preferably welded alternately on the top and bottom of the panel so produced. The panels are then adapted to be fabricated into the desired building structure. It should be understood that the individual units can be made of any desired size and strength and that the built-up panels can likewise be constructed to the requisite shape and of the necessary strength so that they can be secured together to form a frameless building structure. Likewise the units or panels can be employed to

form substantially any structure such as bridge members and floors, supporting forms for concrete, caissons and the like.

Referring now to the drawings, which illustrate one embodiment of my invention, Fig. 1 is a plan view of a unit constructed in accordance with the principles of the invention; Fig. 2 is a side elevation of the unit shown in Fig. 1; Fig. 3 is an enlarged cross-sectional view through the unit taken on line III—III of Fig. 1; Fig. 4 is a plan view of a horizontal and two vertical panels joined together at their edges to form a frameless building structure mostly broken away, with the panels being made up of the individual units shown in Figs. 1 to 3; Fig. 5 is a vertical cross-sectional view taken on line V—V of Fig. 4; Fig. 6 is a horizontal sectional view through a round column fabricated from the individual units shown in Figs. 1 to 3; Fig. 7 is a horizontal cross-sectional view through a square column fabricated from the units shown in Figs. 1 to 3; and Fig. 8 is a plan view of a piece of sheet metal illustrating the manner in which the individual sheet metal strips are cut therefrom without waste.

The embodiment of the building unit of my invention, illustrated in detail in Figs. 1 to 3 of the drawings, comprises three load-carrying members 10, 11 and 12, which are preferably angle-irons as shown but which may be any other rolled metal sections, such as channels or T-bars. The selection of the particular section of the members 10, 11 and 12 depends largely on the use to which the member is put, i. e., for floors, walls, ceilings, etc. The members 10, 11 and 12 are secured to the center and edge portions of a strip of sheet metal indicated generally by the numeral 13. The sheet metal strip 13 has a flat central portion 14 which is preferably spot-welded to the angle-iron 10 at longitudinally-spaced points 15 so that the angle-iron is in the full-line position shown. However, the invention contemplates welding the angle-iron 10 in the dotted-line position shown as well as to increase the thickness of the unit formed. The side portions of the sheet metal strip 13 are bent at equal but opposite angles to the central portion 14 and may comprise triangularly-shaped tab portions 17 which have their ends 18 bent parallel to the flat central portion 14 of the sheet metal strip and spot-welded as at 19 to the angle-irons 11 and 12. The angle-irons 11 and 12 can be welded in the dotted-line position instead of the full-line position if it is advisable to increase the thickness of the unit.

The strength of the unit produced is largely dependent upon its depth or thickness which is the distance between angle-iron 10 and the plane of angle-irons 11 and 12. This distance can be altered in units provided for different purposes by changing the angle the tab portions 17 make with the central portion 14 of the metal strip. To increase the distance increases strength. Ordinarily the tab portions are bent at an angle of about 45°. The strength of the units can also be increased by making the sheet metal heavier and broadly the invention contemplates using metal plate of any requisite thickness to provide the desired strength together with members 10, 11 and 12 of increased strength. Also under other conditions where the units are used for partitions or for like purposes where little strength is required the sheet metal can be quite thin and the members 10, 11 and 12 can be flat-rolled sections if desired.

The members 10, 11 and 12 preferably are formed with longitudinally spaced apertures 21 by

a punching or other operation to facilitate fastening veneering or facing materials to the formed units as hereafter explained.

The individual units, as just described, are adapted to be incorporated into panels and this is accomplished by the provision of sheet metal channels 25 which receive the ends of a plurality of units placed in a side-by-side relation. Channels 26 likewise preferably bound the sides of the end units with the channels 25 and 26 being welded together at their ends and with the individual units being welded to the channels at their points of engagement. It should be noted here that the units can be made in half widths, as hereinafter more fully explained, and that these half-width units are preferably used at the extreme sides of the units placed side-by-side to form a panel as a seen in Fig. 4.

To further strengthen the panel structure and to positively tie the individual units together and form a truss-like structure, metal sections 30, extending transversely of the units at spaced intervals, as best seen in Figs. 4 and 5, are provided and are welded to the tops of the individual units at their points of contact. Metal sections 31 likewise are employed which secure together the bottom of the units forming the panel. The metal sections 31 are, of course, welded to the individual units and to the channels at their points of contact. To improve the truss structure the metal sections 30 and 31 are positioned substantially midway between each other with the bottom metal sections 31 being secured to the longitudinal angles 11 and 12 at substantially the same points that the edge portions 18 of the triangular tabs 17 are secured. Thus the upper metal sections 30 are joined to the base 14 of the sheet metal strip 13 at the narrow portion connecting the triangular tabs of the sheet metal strip.

The metal sections 30 and 31 are preferably in the form of angle-iron sections when employed on the top of floors or wherever they must resist compression and are preferably flat-rolled sections when used on the under side of floors or wherever they resist only tension or light loads. Broadly, however, they may comprise any metal section such as channels, T-bars etc., best adapted to provide the requisite strength or to receive covering or veneering surfaces.

While in the preferred form of the invention the metal sections 30 and 31 extend transversely of the panels they may also be secured diagonally or criss-cross of the panels to further improve the truss structure or to facilitate the application of covering or veneering materials to the panels.

The panels formed by the fabrication of the units are adapted to be employed as floors, exterior or interior walls, partitions, sloping ceilings or roofs or the like and, as seen in Figs. 4 and 5, one panel, indicated as a whole by the numeral 40, is employed as a floor, and other panels, identified by the numerals 41 and 42, are used as walls with the panels being supported on a suitable foundation 35. The edges of the panels, where they come together at the base of the wall and at the edge of the floor, are welded together as at 36 during building and on location. It should be understood that the particular structure shown in Figs. 4 and 5 is merely a fragment of the frameless structure and that several more floors, various walls, and so forth, can be incorporated in the structure without necessitating other supporting means than the foundation 35.

which may be of any known type. The various points of joinder between the individual panels are positively welded together in the field to provide a very strong rigid structure of the frameless type. The interior and exterior walls or partitions can be of load-bearing or non-load-bearing type with the latter being made lighter in weight and of relatively less strength.

The panels are made of any size or shape as controlled by the use to which they are put. For example, the panels can be large enough to form a whole wall, ceiling or floor, or they can be made in say six-foot widths to be more convenient for shipping and handling. These unit panels are then welded together on location to form complete panels constituting whole walls, floors, etc.

It should be appreciated that the panels are formed in other than square shape if desired. Polygonal, round, oval and other shapes can be made and the channels bounding the edges of the assembled units can be at an angle to the sides and end of the units which are appropriately cut to be properly received and secured in the channels. Thus substantially any type of structure can be made up because of the adaptability of my invention to the ready and facile fabrication of panels and units of various types, shapes, sizes and strengths.

One feature of my invention which is noteworthy and which is believed novel is that the construction and shape of my units and panels adapt them to the module system of building and architecture. This popular system, briefly, is that the architect and builder bases his design and arrangement on modules or squares of a certain size, say three feet square. A living room, for example, could then be five modules long, four wide and three high. A hall could be two modules wide, three high and five long, etc. My units readily fit into the module system of planning and building in that each unit is made of a standard module width or half width and the squares of connected sheet metal of each unit likewise form modules of length. Accordingly the fabrication of buildings is simplified and expedited and a new and novel relation is established between architectural and building design and materials for constructing the designed structures.

It should be understood that the frameless building structure herein disclosed is not ordinarily adapted for use as a skyscraper or other tall building but that it can beneficially be employed to construct small buildings of several stories, and it is particularly adapted for the construction of homes, stores, and the like.

Where it is found necessary in a frameless structure to provide means for carrying additional or greater weight, columns or beams can be produced by fabricating the individual units of my invention in a plurality of different ways. For example, as seen in Figs. 6 and 7, a plurality of the units has been made into a circular column, indicated generally by the numeral 43, having their contacting edges welded together with the column further strengthened with welded-on circular metal sections 44. Thus a column of any desired strength can be provided depending upon the size and strength of the individual units.

Fig. 7 shows a column or beam 45 formed of four of the units welded together at their edges. can be used as a beam. In this particular, This structure can be employed as a column or invention contemplates a frameless structure adapted to house relatively heavy machinery or

to be adapted to carry extra heavy loads under certain circumstances in which load-carrying means are provided in the form of additional columns in the structure with load-carrying beams extending across the columns or spanning the foundation. Lighter beams or columns can be made from either two or three of the units fabricated as just described, as will be evident.

The method of manufacturing my improved unit and fabricating the same into panels of any desired size and strength is believed novel. Briefly, it comprises taking a relatively large sheet of sheet metal, such as indicated by the numeral 50 in Fig. 8, and in cutting the sheet without waste on the dotted lines 51 in the drawing. Thus a plurality of strips of sheet metal is provided having the laterally extending tabs or portions 17 at periodic, longitudinally-spaced distances on each strip. The strip is press- or roll-bent along its central longitudinal plane so that the triangular tabs extend at opposite but similarly inclined angles to the flat base portion 14. Each of the bent strips is fabricated into a unit by securing the longitudinally-extending load-carrying members 10, 11 and 12 to the central portion and to the extreme edge portions of the strip.

All of the strips formed, as above described, are whole strips of the desired shape except those at the sides of the sheet which, as seen at the top of Fig. 8 of the drawings, are half widths. These half-width strips are fabricated similarly to the whole strips but with only the tabs bent from the continuous edge portion and with only two load-carrying members being used. The half-width units are employed at the sides of the panels or wherever else they can advantageously be utilized to provide a panel or unit of the requisite dimensions.

Securing the load-carrying elements to the strip is rapidly and efficiently done, in commercial manufacture under my process, by spot-welding. The individual units are then fabricated into the panels of desired size and strength as has been explained above, with the panels being built into a frameless building structure on location. If desired the panels also can be made up on location from the individual units which will facilitate shipment of material to the job as the triangular shape of the units permits them to be nested in each other for handling and shipment.

While the invention has been particularly described as employing spot-welding or broadly welding for securing the parts of the units together, and the units into panels, and the panels into a building, it should be recognized that while this is the preferred practice and is believed novel as described, the invention contemplates employing other securing means, such as rivets, bolts, clips or other accessories.

From the foregoing description of one embodiment of my invention, it will be evident that a building unit, adapted for use with the module system of architectural planning, has been provided which is relatively inexpensive to manufacture by commercial methods and apparatus and which is strong and light and adapted to be fabricated into any desired building structure on location with most of the part assembling being done in the manufacturing plant before shipment to location. A relatively smaller amount of metal is used in the unit than has heretofore been the practice, further reducing the manu-

facturing cost as well as the weight of the unit in the fabricated structure.

There are a number of novel features about the invention which have not been discussed heretofore as, for example, the geometric configuration of the individual units and the fabricated panels, as well as the actual construction thereof, is so pleasing in appearance that under certain conditions the panels can be left entirely exposed and painted or otherwise decorated to provide a pleasing wall or ceiling. This is particularly true in garages, stores, or other buildings, in which the open appearance of the structure is not undesirable. Ordinarily the panels are covered in any known or suitable manner as, for example, in floors by the provision of metal screening with a covering of cement thereon or with a wooden floor being laid directly over the panel. For walls, metal lath can be wired to the panels and covered in the usual manner by plaster, cement, stucco, brick or wood. Again, the panels forming walls can be provided with a glass or a silk covering with lights being employed in the panels and shining through the glass or silk to provide an indirect lighting system. In a similar manner the panels adapt themselves to the panel system of heating. The open character of the construction permits the ready laying of, and access to wiring, plumbing, etc., and likewise the structure is particularly adapted for air-conditioning means, insulation, heating ducts and the like.

I have found that when employing my building units and panels they can be assembled to provide cantilever extensions over window and door openings and canopies, balconies, floors and roofs can likewise be made with cantilever extensions. These extensions are of such strength in proportion to their weight that a very strong rigid building structure is provided by their fabrication in the manner herein disclosed.

While in accordance with the Patent Statutes I have illustrated and described one embodiment of my invention it should be understood that the invention is not limited thereto or thereby but is defined in the appended claims.

I claim:

1. A fabricated frameless metal structure adapted for use as a floor, side wall or the like in a building, said structure including a plurality of units placed in side-by-side relation, each unit comprising three angle-irons extending lengthwise of the unit and positioned to define a triangle, a sheet metal strip likewise extending lengthwise of the unit and spot-welded along a longitudinal line to one of the angle-irons, triangular laterally-extending portions formed integrally with the lateral edges of the sheet metal strip and bent at an angle thereto into contact with the remaining angle-irons where the portions are spot-welded, sheet metal channels receiving the ends of the units which are welded thereto, and tension-resisting metal sections extending laterally of the units and welded thereto, said sections being positioned on the bottom surface of the structure adjacent the ends of the tabs and compression-resisting metal sections welded on the top of the structure midway between the bottom sections.

2. A fabricated frameless metal structure adapted for use as a floor, side wall or the like in a building, said structure including a plurality of units placed in side-by-side relation, each unit comprising three metal sections extending lengthwise of the unit and positioned to define a triangle, a sheet metal strip likewise extending lengthwise of the unit and spot-welded along a

longitudinal line to one of the metal sections, triangular laterally-extending portions formed integrally with the sheet metal strip and bent at an angle thereto into contact with the remaining metal sections where the portions are spot-welded, and sheet metal channels receiving the ends of the units which are welded to the channels.

3. A fabricated frameless metal structure adapted for use as a floor, side wall or the like in a building, said structure including a plurality of units placed in side-by-side relation, each unit comprising three angle-irons extending lengthwise of the unit and positioned to define a triangle, a sheet metal strip likewise extending lengthwise of the unit and spot-welded along a longitudinal line to one of the angle-irons, and laterally-extending areas formed integrally with the lateral edges of the sheet metal strip and bent at an angle thereto into contact with the remaining angle-irons where the areas are spot-welded.

4. A fabricated frameless metal structure including a plurality of units placed in side-by-side relation, each unit comprising three angle-irons extending lengthwise of the unit and positioned to define a triangle, a sheet metal strip likewise extending lengthwise of the unit and secured along a longitudinal line to one of the angle-irons, and triangular laterally-extending portions formed integrally with the lateral edges of the sheet metal strip and bent at an angle thereto into contact with the remaining angle-irons where the portions are secured.

5. A metal building unit capable of being fabricated into walls, floors, columns and similar building structures, said unit including a strip of sheet metal having a flat central portion with similarly but oppositely-inclined edge portions, said edge portions being in the form of triangular portions with the extreme lateral edges thereof being parallel to the central portion of the sheet, and rolled metal sections spot-welded to the flat central portion and to the extreme lateral edges of the strip.

6. A metal building unit capable of being fabricated into walls, floors, columns and similar building structures, said unit including a strip of sheet metal having a flat central portion with similarly but oppositely-inclined edge portion extending at longitudinally-spaced intervals from the flat central portion, and angle-irons welded to the flat portion and to the extreme lateral edges of the strip.

7. A metal building unit capable of being fabricated into walls, floors, columns and similar building structures, said unit including a strip of metal having a flat base portion with similarly but opposite-inclined edge portions, and longitudinally-extending strengthening means secured to the flat base and to the extreme lateral edges of the strip.

8. A metal building unit capable of being fabricated into walls, floors, columns and similar building structures, said unit including a strip of sheet metal having a flat base with similarly but oppositely-inclined edge portions, said edge portions being in the form of triangular tabs with the extreme lateral edges thereof being parallel to the base of the sheet, and longitudinally-extending strengthening means secured to the flat base and to the extreme lateral edges of the strip.

9. A building unit comprising three triangularly-positioned, longitudinally-extending elements and sheet metal substantially in the form of square plates bent on a diagonal line connecting one pair of opposite corners of the squares.

and secured in the region of the bend to one of the elements and secured to the other elements by the corners of the squares opposite the bend.

10. A building unit comprising three triangularly-positioned, longitudinally-extending rolled metal sections and sheet metal substantially in the form of connected square plates bent on a diagonal line connecting the corners of the squares and spot-welded in the region of the 5 bend to one of the metal sections and spot-welded to the other metal sections by the corners of the squares opposite the bend.

11. In combination, a plurality of building units placed side by side and received at their 15 ends in sheet metal channels to which the units are welded and laterally-extending metal sections welded on both sides of the units and securing the units together, each of said units including three triangularly-positioned longitudinally-extending angle-irons and a single piece 20 of sheet metal welded to and connecting the angle-irons, said sheet metal being in the form of diagonally-connected polygons.

12. In combination, a plurality of building 25 units placed side by side and received at their

ends in sheet metal channels to which the units are welded and laterally-extending rolled metal sections welded on both sides of the units and securing the units together, said metal sections being spaced alternately on the opposite sides of 5 the units.

13. A frameless building comprising walls and floors constructed of units formed of angle-irons connected by sheet metal spot-welded to the angles, the units being received at their ends in 10 sheet metal channels to which the units are welded, lateral tie rods connecting the units and together with the channels forming the units into panels, the panels being welded together to form the frameless building.

14. A frameless building comprising a plurality of panels welded together to form the floors, walls and the entire structure of the building, said panels being made up of individual units placed in side-by-side relation and connected by welded- 20 on lateral ties, and sheet metal channels surrounding the sides of the connected units and welded thereto and forming the panels of the proper size.

WALTER H. STULEN. 25
